UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP, HAVING AS TRUSTEES F. B. TOWNE, E. S. TOWNE, J. M. TOWNE, AND F. W. WILSON.

LOCKING MEANS FOR TELESCOPING ELEMENTS.

Application filed September 22, 1923. Serial No. 664,278.

To all whom it may concern:

Be it known that I, JOHN SCHADE, a citizen of the United States, residing at the city of Holyoke, in the county of Hampden and State of Massachusetts, have invented 5 certain new and useful Improvements in Locking Means for Telescoping Elements; and I do declare the following to be a full, clear, and exact description of the invention, 10 such as will enable others skilled in the art to which it appertains to make and use the same.

This invention relates to locking means for flat telescoping elements, and has for 15 its object to provide very simple and effective means of this description, not likely to get out of order, and readily applied for use.

Further objects of the invention will appear from the following description supplemented by the drawings, in which latter:

Figure 1 is a plan view showing the invention applied to an ordinary loose leaf binder—

Figure 2 is a section at the line 2—2 of 25 Figure 1, showing the telescoping elements locked—

Figure 3 is likewise a section at the line 2—2 of Figure 1, but showing the telescoping elements closed and unlocked—

Figure 4 is a detail perspective of the lock bar—

Figure 5 is a view similar to Figure 2, but showing the lock bar removed—

Figure 6 is a view similar to Figure 3 35 but showing more particularly a modified form of lock bar—

Figure 7 is a section at the line 7—7 of Figure 1—

Figure 8 is a view similar to Figure 1, 40 but looking in an opposite direction with the outer telescoping element partly broken away and sectioned, and showing a further modification of the invention, in which the locking dog is pivoted to said outer element 45 and is adapted to lock against the inner telescoping element—

Figure 9 is a section at the line 9—9 of Figure 8, and

Figure 10 is a section at the line 10—10 50 of Figure 8.

Similar numerals of reference denote like parts in the several figures of the drawing.

While the invention is applicable to flat

telescoping parts such as are used in various arts, the invention will be clearly understood when illustrated in connection with loose leaf binders, and therefore such an illustration is particularly shown in the drawings.

The parts of the loose leaf binder will be 60 briefly referred to, without any detailed description since such parts are well-known.

1, 2, are the usual cheek pieces of the binder carrying respectively the complementary hinge elements 3, 4, and to these 65 cheek pieces are respectively secured throughout their length the plates 5, 6, having the usual bottom portions 7, 8, one of which overlaps the other in sliding relation.

The end extremities of these bottom portions are bent upwardly at right angles so as to form telescoping elements 10, 9, capable of sliding one within the other.

The elements above described form a 75 part of the construction of an ordinary loose leaf binder, and no further description of the latter is deemed necessary in the present instance.

Pivoted to the inner telescoping element 10 is a locking dog 11 whose nose 12 extends upwardly through an opening 13 in the upper wall of said element, and extending outwardly at right angles to the tail 14 of the dog is a lug 15, and 16 is a spring suitably 85 secured within said element and whose free end bears upwardly against the bottom of the tail 14, so that it will be readily understood that this spring is constantly exerting a force that will cause the nose of the dog 90 to be impinged against the upper portion of the telescoping element 9, so as to lock together the elements 9 and 10.

Slidably contained within the telescoping element 10 is a lock bar 18 which has a part 95 19 that extends outwardly and is flanged over and above the upper portion of the telescoping element 10, this part being merely used for the ready manipulation of the lock bar, and the latter is confined in 100 position by lips 21, 22, that are bent downwardly from the upper portion 10.

23 is an inclined slot cut through the bar 18 the lower end of the slot terminating in a straight portion 24, and through this slot 105 extends the lug 15, so that it will be clear

that when the lock bar is moved inwardly the lower wall of this slot 23 will swing the tail 14 of the dog so that the nose 12 will be firmly impinged against the telescoping element 9, and thus lock the telescoping sections together, and when the lock bar is moved outwardly, the upper wall of the slot 23 will force the tail of the dog downwardly and cause the nose 12 to be withdrawn 10 from its locking position, and the lug 15 will then be in the straight portion 24 of the slot so that there can be no accidental movement, accentuated by the spring 16, which would effect the complete 15 or partial locking position of the nose 12. But this straight portion 24 of the slot 23 is merely precautionary and is not at all necessary.

It will be manifest that the action of the 20 walls of the slot 23 will alone be sufficient to effect the locked and unlocked positions of the dog 11 without the spring 16, but this spring always tends to urge the nose of the dog into locking position, and it is 25 possible that, in the absence of the spring, the parts would jar loose from a locking position whereas this would not be possible with the spring present. However, the invention is clearly not limited to the use of 30 the spring, although, in its preferred form, the spring would be embodied in the construction exemplifying the invention herein.

In some instances, particularly in the 35 smaller sizes of constructions that utilize the telescoping elements 9 and 10, the lower wall of the inclined slot will not be found necessary, since the force of the spring itself is sufficient to always urge the nose of the dog into locking position, the lower wall 40 of the slot being merely a positive means for accomplishing this purpose and for incidentally supplementing the action of the spring, and therefore at Figure 6 is illustrated a construction in which this lower 45 wall of the slot is omitted and an opening 25 formed in the lock-bar whose upper wall is inclined like the upper wall of the slot 23, and nothing but the spring itself is utilized to effect the locking position of the dog.

50 Referring particularly to Figures 8, 9, and 10, the elements 10¹, 9, telescope one

within the other as in the instance of the construction shown at Figure 1, the only difference in this respect being that the upper flanged portion of the inner element 55 extends in a direction reverse to that shown at Figure 1, so that there is a space formed between the vertical walls of these elements, and within this space are housed the lock-bar 18¹ and the locking dog 11 which latter 60 is pivoted directly to the inside vertical wall of the outer element 9, while the lock-bar is located between the dog and the vertical wall of the element 10¹ and is operated, by means of a stud 25 that extends 65 through an elongated slot 26 in the vertical wall of the element 9 and is secured to the lock-bar, any convenient knob 27 being carried by this stud outside the slot for convenience in operating.

70 In this modified construction, the operation is precisely the same as in the construction shown at Figure 1 and the locking dog is operated by the inward movement of the lock-bar to force the nose of the dog into locking engagement with the inner telescoping element.

It will accordingly be manifest that it is immaterial which of the telescoping elements carries the locking dog.

80 In structures like loose leaf binders it is preferred to use two of these locking mechanisms, one at each end of the binder, and therefore the drawings show two of these mechanisms, both of which are similar in 85 all respects.

What is claimed is:—

The herein-described locking means for flat telescoping elements, which comprises, 90 in combination with these elements, a locking dog pivoted to one element, a spring which normally forces the nose of said dog into frictional locking contact with the other element, and a bar slidably supported by one of the elements in parallelism with said dog and operatively engaged with the dog whereby the sliding movements of said bar 95 will rock the dog to effect the locking and unlocking positions thereof.

100 In testimony whereof I affix my signature hereto.

JOHN SCHADE.
